MANUAL RESET VALVE

Eugene Paille, Los Angeles, Calif., assignor to
General Controls Co., Glendale, Calif., a corporation of California

Application August 15, 1941, Serial No. 406,979

8 Claims. (Cl. 137—139)

My present invention relates to fluid control valves and particularly to those of the "manual reset" type wherein a closure member, normally biased to closed position, is brought to open position by manual means, in which open position it is retained by means responsive to a controlling condition. Manual reset valves of the type indicated have particular utility for the control of fluid fuel supply to a burner, means responsive to the flame of the burner then being provided for controlling the means by which the valve is maintained in open position. Such means may consist of a thermostatic device, such as an expansion rod, for actuating a latch mechanism; or, more commonly, a thermoelectric generator or thermal cutout may be employed for controlling the energization of electromagnetic holding means. In any event, upon extinction of the burner flame, the holding means become ineffective and the valve closes, manual resetting of the valve then being required for subsequent operation of the burner.

In a burner control system, wherein a manual reset valve is employed for controlling fuel supply to a main burner, for the ignition of which a normally constantly burning pilot burner is provided, it is desirable to provide means for closing the main burner valve during the resetting operation to prevent the possibility of unignited gas being passed in the event the pilot burner has accidentally been extinguished. In the prior art, it has been proposed to provide additional means for closing the valve while moving the closure member into the open position wherein it should be retained by the condition responsive means. It is therefore an object of my invention to obviate the necessity of such additional closing means by providing means whereby the closure member is positively maintained in closed position during the resetting operation and can only subsequently move to open position in the event that there is flame at the pilot burner.

Another object of my invention is to provide means for simultaneously applying a closing force to the closure member while raising an armature into engagement with its electromagnet core; the armature, when unenergized, serving to maintain the closure member in its closed position.

Other objects and advantages of my invention will be found in the description, the drawing, and the appended claims.

For complete understanding of the invention, reference may be had to the following detailed

description and accompanying drawing, wherein:

Figure 1 is a sectional view of a "manual reset" valve embodying my invention;

5 Figures 2 and 3 are fragmentary sectional views of the valve shown in Fig. 1, showing the parts in the positions they assume in operation;

Figure 4 is a fragmentary sectional view of a 10 valve embodying a modified form of my invention; and

Figure 5 is a fragmentary horizontal section taken along the line 5—5 of Fig. 4.

In the drawing, the numeral 11 indicates a 15 valve casing having an inlet 12 and an outlet 13 separated by a partition 14 having a port opening 15 therethrough, the upper end of the wall of which provides an annular valve seat 16. Extending from the bottom wall of the casing 11, centrally of the port 15, is a boss 17 having in its upper end a recess 18 provided with a supplemental annular valve seat 20. By means of a passage 19 the recess 18 communicates with the exterior of the valve casing.

25 Secured between the upper wall of the casing 11 and the flange 24 of a housing 25 is the marginal portion of a flexible diaphragm 26, on the underside of which is a closure member 27, preferably of fibrous material, cooperable 30 with the valve seats 16 and 20, and urged away from the seats by a spring 21 compressed between the closure member and the bottom wall of the casing. On the upper side of the diaphragm 26 is a circular metal disk 28 having in its upper surface a conical recess 29 communicating with the recess 18 by a tubular member 30 extending through openings in the disk 28, diaphragm 26, and the closure member 27. The laterally extending lower end portion of 35 the tubular member 30 provides an auxiliary valve seat 31, while its upper end portion is riveted over to secure the disk 28 and the closure member 27 to the diaphragm 26. The diaphragm 26 serves as guide means for the members 27 and 28. Extending loosely through the tubular member 30 is a valve stem 32 on the lower end of which is an auxiliary closure member 33 cooperable with the auxiliary valve seat 31 and urged toward it by a compression spring 40 34 abutting the lower wall of the recess 18. Differences in fluid pressure on opposite sides of the diaphragm are avoided by an eyelet 35 fastened in an opening in the diaphragm and provided with a fine mesh screen. The eyelet 35 also permits passage of fluid from the inlet

12 to the interior of the housing 25 whence, via the recess 29 and the tubular member 38 it may flow (when member 33 is away from seat 31) to the recess 18 and thence, by passage 19 to the exterior of the valve.

Secured to the underside of the top wall 36 of the housing 25 by screws 37 is a U-shaped electromagnet core 38, about one leg of which is wound an energizing coil 39 connected by lead wires 41 with terminals 40, insulatingly mounted in a side wall of the housing. Slidable in an opening through the housing top wall 36 and the core 38 is a rod 42 having an enlarged end portion 43 forming a button to facilitate manual operation. Compressed against a pin 44 extending through the rod 42 is a spring 45 constantly urging a sliding collar 46 against a fibrous packing 47; thereby preventing any leakage of fuel around the rod 42 to the outside of the casing.

Freely slidable on the rod 42, and guided thereby, is a circular armature 48 cooperable at its upper surface with the pole faces 49 of the core 38. A compression spring 35 urges the armature 48 away from the pole faces 49, but is not of such strength as to overcome the magnetic holding force of the core when the same is energized. The underside of the armature 48 is recessed to receive certain mechanism, to be hereinafter described, while its upside is built up at 54 to maintain a relatively uniform flux path between the core pole faces 49.

Threaded on the reduced lower end portion of the rod 42 is a collar 51 having, on either side thereof, slots for the reception of the inner end portions of arms 52, which arms are held in place by pins on which the arms are free to pivot. The outer portion of the upper side of the circular disk 28 slopes downwardly to form, in conjunction with the periphery of the recess 29, a shoulder 53 which acts as a fulcrum about which the arms rotate upon actuation of the mechanism.

The operation of the device is as follows: assuming that the valve is connected to supply fuel to a main burner and that a pilot burner for the main burner is connected to the supplemental outlet 19 by a pipe 22 having a fitting 23 threaded in the enlarged outer portion of outlet 19; with the parts in the positions shown in Fig. 1, fuel flow to the main burner is obstructed by the closure member 27, and to the pilot burner by the closure members 27 and 33. If the rod 42 is now depressed against the force of spring 34 by applying pressure on button 43, the arms 52, bearing on the shoulder 53, will exert a downward force on the disk 28, thus holding the closure member firmly on its seat 18 against the upward force of spring 21. With the shoulder 53 acting as a fulcrum about which the arms 52 rotate, this downward movement of the inner ends of the arms 52 will cause their outer ends to move upwardly, thus raising the armature 48 into engagement with the pole faces 49 of the core 38 against the compression force of spring 35; the parts assuming the positions shown in Fig. 2. It will be seen that the auxiliary closure member 33 has been forced open by the rod 42 acting on the valve stem 32, permitting gas to flow from the interior of the housing 25 by way of the recess 29, tubular member 38, recess 18, passage 19, and pipe 22 to the pilot burner, where it now may be lighted.

Assuming, now, that the coil 39 is energized 75

by means such as a thermoelectric generator responsive to the flame of the pilot burner, ignition of gas at the pilot burner will soon cause energization of the electromagnet core 38 sufficient to hold the armature against the force of spring 35. If the pressure applied on button 43 is now decreased, spring 34 forces (through valve stem 32) rod 42 upward, thus raising the inner ends of the arms 52. As these ends rise, they no longer transmit the downward force from rod 42 to disk 28, and the main closure member 27 immediately moves away from its seat since the only material force now tending to hold it in closed position is the weight of disk 28 which is overcome by the upward force of spring 21. Auxiliary closure member 33 has not entirely closed when the main closure member leaves its seat, and gas may now also flow from inlet 12, past the supplemental valve seat 20, through recess 18 and passage 19 to the pilot burner; and through port 15 and outlet 13 to the main burner. Release of rod 42 will permit spring 34 to move closure member 33 to its fully closed position; the parts assuming the positions shown in Fig. 3. Upon accidental extinction of the pilot burner flame, the electromagnet is no longer energized and armature 48 moves downwardly under the force of spring 35. The force of this spring, in combination with the force of gravity acting on armature 48 and disk 28 is sufficient to overcome the counter force of springs 21 and 34 to close the main and supplemental ports; the parts re-assuming their normal positions as shown in Fig. 1. It will be apparent that if the weight of members 28 and 48 is made sufficient to overcome springs 21 and 34, spring 35 may be omitted. Spring 34 obviously exerts a greater closing force on auxiliary closure member 33 than spring 45 exerts on rod 42, in order to insure the seating of auxiliary closure member 33.

The modified form of my invention shown in Figs. 4 and 5 is similar to that shown in Figs. 1-3, the only essential difference being that a single resilient member is substituted for the two arms 52 of Figs. 1-3. Firmly held between two nuts 61 threaded on the lower end portion of the rod 42, is a normally flat elongated resilient member 62, the mid portions of which are engageable, in operation, with the shoulder 53 of the disk 28. The resilient member 62 is reduced in width at its outer portions, as shown in Fig. 5, to prevent lateral buckling when forced against the shoulder 53. The operation and results are the same as in the mechanism shown in Figs. 1-3, i. e., downward movement of rod 42 causes the resilient member 62, fulcrumed on shoulder 53, to flex, exerting a downward force on disk 28 and, through its outer ends, an upward force on armature 48. The positions assumed by the members 62 and 48 when operated are shown in broken lines in Fig. 4. A spring 70 serves the dual purpose of urging the main closure member 27 toward its seat while constantly exerting pressure on a metal washer 72 to hold a fibrous packing 73 against the core 38 to prevent leakage of gas around rod 42 to the exterior of the casing.

It will be seen that manipulation of the rod 42 can never effect opening of the main valve unless the electromagnet is energized.

While I have herein shown and described, by way of illustration, specific embodiments of my invention, I wish it to be understood that modifications may be made without departing from the spirit of my invention and that I intend

therefore, that my invention be limited only by the scope of the appended claims.

I claim as my invention:

1. In a fluid control valve: a casing having a ported passage therethrough provided with a valve seat; a closure member cooperable with said seat; a first means constantly urging said closure member away from its seat; a second means normally urging said closure member toward its seat with a force greater than that of said first means; a lever having a portion interposed between said closure member and said second means; means on the closure member forming a fulcrum for said lever; means extending to the exterior of the casing for operating said lever; said lever being movable in one direction to simultaneously create a force tending to hold said closure member on its seat and move said second means to a first position wherein its force on the closure member is removed; and condition responsive means for retaining said second means in said first position; said lever being movable in an opposite direction to a position wherein, when said second means is retained by said condition responsive means, the lever no longer exerts said force tending to hold said closure member on its seat.
2. In a fluid control valve: a casing having a ported passage therethrough provided with a valve seat; a closure member cooperable with said seat; a first means constantly urging said closure member away from said seat; a second means, including a movable armature, normally urging said closure member toward its seat with a force greater than that of said first means; a lever having a portion interposed between said closure member and said armature; means on the closure member providing a fulcrum for said lever; means extending to the exterior of said casing for actuating said lever; said lever being movable in one direction to simultaneously create a force tending to hold said closure member on its seat and to move said armature to a first position wherein the force of said second means on said closure member is removed; and electromagnetic means for retaining said armature in said first position; said lever being movable in an opposite direction to a position wherein, when said armature is retained by said electromagnetic means, the lever no longer exerts said force tending to hold said closure member on its seat.
3. In a fluid control valve: a casing having a ported passage therethrough provided with a valve seat; a closure member cooperable with said seat; a first means constantly urging said closure member away from said seat; a second means, including a movable armature, normally urging said closure member toward its seat with a force greater than that of said first means; a resilient lever having a portion interposed between said closure member and said armature; means on the closure member providing a fulcrum for said lever; a reciprocable rod extending through said armature and said casing to the exterior thereof for actuating said lever; said lever being movable in one direction to simultaneously create a force tending to hold said closure member on its seat and to move said armature to a first position wherein the force of said second means on said closure member is removed; and condition responsive electromagnetic means for retaining said armature in said first position; said lever being movable in an opposite direction, by the actuation of said rod, to a position wherein, when said armature is re-
- 5 tained by said electromagnetic means, the lever no longer exerts said force tending to hold said closure member on its seat.
4. In a fluid control valve: a casing having a ported passage therethrough provided with a valve seat; a closure member cooperable with said seat; a first means constantly urging said closure member away from said seat; a second means, including a movable armature, normally urging said closure member toward its seat with a force greater than that of said first means; pivoted lever arms interposed between said closure member and said armature; means on the closure member providing a fulcrum for said lever arms; a reciprocable rod extending through said armature and said casing for actuating said lever arms and providing, on its inner end portion, means for pivoting said lever arms; said lever being movable in one direction to simultaneously create a force tending to hold said closure member on its seat and move said armature to a first position wherein the force of said second means on said closure member is removed; and condition responsive electromagnetic means for retaining said armature in said first position; said lever being movable in an opposite direction to a position wherein, when said armature is retained by said electromagnetic means, the lever no longer exerts said force tending to hold said closure member on its seat.
- 10 5. In a fluid control valve: a casing having a ported passage therethrough provided with a valve seat; a closure member movable toward and away from said seat to control fluid flow through the valve; means constantly biasing said closure member toward open position; means located at the side of said closure member away from said seat for normally urging the closure member toward its seat with a force greater than that produced by said biasing means; said last-named means including a member movable on the axis of said closure member toward and away from the same; a rod reciprocable in a central opening in said movable member; mechanical means interposed between the closure member and the movable member and connected to said rod; said last-named means being effective when said rod is moved in one direction to create a force tending to urge the closure member against its seat and simultaneously to move said movable member in a direction away from the closure member to a position wherein its force thereon is removed; and means responsive to a controlling condition for retaining said movable member in said moved position; said mechanical means being effective when said rod is subsequently moved in an opposite direction to relieve the force produced by said mechanical means, whereby the closure member is free to move to its open position under the influence of said constant bias.
- 15 6. In a fluid control valve: a casing having a ported passage therethrough provided with a valve seat; a closure member movable toward and away from said seat; means constantly biasing said closure member toward open position; means adjacent the side of said closure member away from said seat for normally urging the closure member toward its seat with a force greater than that produced by said biasing means; said last-named means including a member movable on the axis of said closure member toward and away from the same; a rod reciprocable in a central opening in said movable member; lever elements interposed between said closure member and said movable member and
- 20
- 25
- 30

connected to said rod; said elements extending on opposite sides of said rod and free to pivot thereon; means on said closure member providing a fulcrum for said elements; said elements being effective when said rod is moved in one direction to create a force tending to urge the closure member toward its seat and simultaneously to move said movable member in a direction away from the closure member to a position wherein its force thereon is removed; and means responsive to a controlling condition for retaining said movable member in said moved position; said lever elements being effective when said rod is subsequently moved in an opposite direction to relieve the force produced by the elements, whereby the closure member is free to move to its open position under the influence of said constant bias.

7. In a fluid control valve: a casing having a ported passage therethrough provided with a valve seat; a closure member movable toward and away from said seat; means constantly biasing said closure member toward open position; means adjacent the side of said closure member away from said seat for normally urging the closure member toward its seat with a force greater than that produced by said biasing means; said last-named means including a member movable on the axis of said closure member toward and away from the same; a rod reciprocable in a central opening in said movable member; a resilient element interposed between said closure member and said movable member and connected to said rod; means on said closure member providing a fulcrum for said element; said element being effective when said rod is moved in one direction to create a force tending to urge the closure member toward its seat and

simultaneously to move said movable member in a direction away from said closure member to a position wherein its force thereon is removed; and means responsive to a controlling condition for retaining said movable member in said moved position; said resilient element being effective when said rod is subsequently moved in an opposite direction to relieve the force produced by the element whereby the closure member is free to move to its open position under the influence of said constant bias.

8. In a fluid control valve: a casing having a ported passage therethrough provided with a valve seat; a closure member cooperable with said seat; a spring constantly urging said closure member away from its seat; a spring-biased member normally urging said closure member toward its seat with a force greater than that of said spring; a lever having a portion interposed between said closure member and said spring-biased member; means on one of said members forming a fulcrum for said lever; means extending to the exterior of the casing for operating said lever; said lever being movable in one direction to simultaneously create a force tending to hold said closure member on its seat and to move said spring-biased member to a first position wherein its force on the closure member is removed; and condition responsive means for retaining said spring-biased member in said first position; said lever being movable in an opposite direction to a position wherein, when said spring-biased member is retained by said condition responsive means, the lever no longer exerts said force tending to hold said closure member on its seat.

EUGENE PAILLE.
